UNITED STATES PATENT OFFICE.

ADOLFO CAMPOS, OF PHILADELPHIA, PENNSYLVANIA.

PICTURE HANGER.

Application filed October 10, 1927. Serial No. 225,143.

The present invention relates to improvements in picture hangers and has for its principal object to provide a supporting device for the picture which is adapted to be attached to a wall or other suitable support, means being associated with the hanger whereby the picture may be tilted to any predetermined position.

Another important object of the invention is to provide a picture hanger wherein the same includes a stationary rod member, a unit being slideable on the lower portion of the rod and which unit is secured at its lower portion to the lower edge portion of the picture, resilient means being associated with the unit and the supporting rod for maintaining the unit in an upwardly urged position, additional means being provided for attachment to the upper edge portion of the picture, and which last mentioned means is operable to adjust the picture to any predetermined tilted position.

A still further object of the invention resides in the provision of a picture hanger which is capable of accommodating pictures or other similar articles of various sizes for supporting the same on a wall, the hanger being secured to the wall by a single bracket thus preventing the defacement of the wall such as frequently results with the use of picture hangers that employ a number of wall attaching brackets.

A still further object is to provide a picture hanger of the above mentioned character which is simple in construction, inexpensive, strong and durable and further well adapted to the purposes for which it is designed.

Other objects and advantages will become apparent during the course of the following description when taken in connection with the accompanying drawings.

In the accompanying drawings forming a part of this application, and in which like numerals indicate like parts throughout the same:

Figure 1 is a front elevation showing the hanger in use.

Figure 2 is a rear elevation.

Figure 3 is a sectional view taken substantially on the line 3—3 of Figure 2 looking in the direction of the arrows.

Figure 4 is a side elevation of the picture hanger showing the manner in which the same supports a picture, and

Figure 5 is a bottom plan view of the suspension chain adjusting means.

In the drawings wherein for the purpose of illustration is shown the preferred embodiment of my invention, the numeral 1 designates an elongated vertically disposed rod, the upper end of which is bent laterally to form a forwardly extending arm 2 in the manner as clearly illustrated in Figure 4. The intermediate portion of this laterally extending arm is bent back upon itself and the looped portion 3 is disposed upwardly in the manner as also clearly illustrated in Figure 4.

The free end portion is disposed rearwardly along the outer end portion of the arm 2 as illustrated at 4 with reference more particularly to Figure 5 and this free end portion is coiled around the intermediate portion of the arm 2 as at 5 and then is directed downwardly to form an angular brace portion 6 the free end of which is coiled about the upper portion of the vertical rod 1 as at 7.

An attaching bracket 8 is adapted to be secured to a wall or other supporting surface by any appropriate fastening means such as shown at 9 and this bracket is formed with a pair of laterally extending ears 10 and 11 respectively at its upper and lower edges. These laterally extending ears are formed with registering openings through which the rod 1 is disposed and the free edge of the upper ear 10 is bent upwardly as at 12 and the upwardly disposed portion is notched to accommodate the inner end portion of the forwardly extending arm 2 so that said rod and arm will be maintained in the vertical position against swinging movement. The manner in which the rod is disposed in the notched and upwardly projecting lip 12 is clearly illustrated in Figures 2 and 4 of the drawings.

A plate-like portion 13 is secured at its inner end to the bottom of the arm 2 and the adjacent abutting rearwardly extending free end portion 4. Extending through this plate and between the arm and the rearwardly extending portion is a pin 14. A pulley 15 is secured on the upper end of this pin while disposed on the lower end of the pin is the gear 16, the same being disposed below the plate 13.

Cooperating with the gear 16 is the transversely disposed worm 17, the same being

carried by the inner end of a shaft 18 which is journaled through a pair of depending brackets 19 formed on the plate 18 at its respective side edges. A thumb engaging member 20 is arranged on the outer end of the shaft 18 to facilitate the manual rotation thereof whereby to effect a rotation of the pin 14 and the pulley 15 carried thereby for the purpose of winding or unwinding a chain 21 which is secured at one end to the drum or pulley, and the free end of which extends through the looped portion 3 and downwardly through an opening 22 provided therefor in the outer end portion of the plate 13. A clasp 23 of any conventional construction is carried by the free end of this chain and the purpose of the chain and the clasp associated therewith will be hereinafter more fully described.

20 My improved picture hanger furthermore includes the provision of a unit designated by the numeral 24 and which is slidably associated with the lower end portion of the vertical rod 1. This unit includes a substantially inverted U-shaped frame formed from a single strand of wire, the base portion 25 of which is provided with a loop 26 through which the rod 1 extends. The free ends of the arms of this inverted U-shaped member 30 are bent to form eyes 27 and extending through these registering eyes is the intermediate portion 28 of an additional substantially inverted U-shaped frame, the base portion 29 of which is offset at its intermediate portion as at 30, and the intermediate portion of the offset central section of the base is formed with a guide 31 for the rod 1 in the manner also as clearly illustrated in Figures 2 and 3.

40 The free ends of the arms of the last mentioned U-shaped frame are formed with hooks indicated at 32 and these hooks are adapted to engage in suitable eyes 33 which are attached to the rear face of the picture A 45 adjacent the lower edge thereof and also at the corners.

An expandible coil spring 34 encircles the vertical rod 1 and this coil spring is disposed between the base portion 25 of the first mentioned inverted U-shaped frame, and the intermediate offset portion 28 of the base of the last mentioned frame comprising the unit 24 in the manner as clearly illustrated in Figure 2. A collar or sleeve 35 is slideable on the rod 1 and is disposed below the lower end of the coil spring for engagement therewith, this collar being adjustable on the rod by means of the set screw 36. The purpose of this adjustable collar or sleeve is to 60 provide a means for adjusting the tension of the expandible coil spring 34 and this spring normally urges the slidable unit 24 upwardly on the vertical rod 1 so that the hooks 32 will be maintained in positive engagement with the eyes 33 carried by the

lower edge portion of the picture A. A head 37 is formed on the lower extremity of the vertically disposed rod 1 for preventing the displacement of the unit 24 from the rod in a manner readily obvious from the construction shown.

This slidable unit 24 will permit the hanger to be used in hanging pictures of various sizes, and when the clasp 23 carried by the free end of the chain 21 is attached to suitable screw eye which is secured to the rear face of the picture at the upper edge portion of the intermediate portion thereof, the picture will be properly suspended by the hooks 32 cooperating with the eyes 33 and by winding or unwinding the chain 21 with respect to the pulley 15, the angle at which the picture may be tilted can be controlled.

A picture hanger of the above mentioned character will at all times be positive and efficient in supporting a picture or the like on a wall or other suitable support, and it will only be necessary to employ one bracket for attaching the rod 1 to the wall, thereby preventing any unnecessary defacing of the wall. Furthermore, due to its simplicity, the adjustment of the picture to any desired angle may be attained without necessitating the removal of the picture from the hanger.

While I have shown the preferred embodiment of my invention, it is to be understood that various changes in the size, shape and arrangement of parts may be resorted to, without departing from the spirit of the invention and the scope of the appended claims.

Having thus described the invention, what I claim as new and desire to secure by Letters Patent is:

1. In a picture hanger of the class described, a vertically disposed member adapted to be secured to a wall, a forwardly extending arm on the upper end of said member, a manually operable pulley supported on the outer end portion of said arm, a flexible suspension member secured at one end to the pulley and adapted to be wound therearound, the free end of said flexible member adapted for attachment to the upper portion of a picture, means arranged on the lower portion of said vertical member for attachment to the lower edge portion of the picture, said last mentioned means comprising a vertically adjustable unit, and a hook and eye connection between the unit and the picture at its lower edge to afford a pivotal connection for the lower edge portion of the picture.

2. In a picture hanger of the class described, a vertical rod, a forwardly extending arm on the upper end of the rod, a unit slideable on the lower portion of the rod, said unit comprising upper and lower inverted U-shaped members operatively con-

nected together, the lower ends of the arms of the lower inverted U-shaped member formed with upwardly disposed hooks, eye members carried by the lower portion of a picture with which said hooks engage, resilient means encircling the vertical rod for disposition between the base portions of said inverted U-shaped members to urge the unit

upwardly on the rod and maintain the hooks in positive engagement with the respective 10 eye members, and suspension means carried by the forwardly extending arm for attachment to the upward portion of the picture.

In testimony whereof I affix my signature.

ADOLFO CAMPOS.
